UNITED STATES PATENT OFFICE.

ALAN ERNEST LEOFRIC CHORLTON, OF MANCHESTER, ENGLAND.

FLUID-PRESSURE ENGINE.

1,078,830.

Specification of Letters Patent.

Patented Nov. 18, 1913.

Application filed June 25, 1912. Serial No. 705,696.

To all whom it may concern:

Be it known that I, ALAN ERNEST LEOFRIC CHORLTON, a subject of the King of Great Britain, residing at Salford Iron Works, Manchester, in the county of Lancaster, England, have invented certain new and useful Improvements in Fluid-Pressure Engines, of which the following is a specification.

10 This invention relates to fluid pressure engines of the so-called "unaflow" type and to internal combustion engines of the duplex valveless type, in which two cylinders placed side by side are connected together at their ends through communicating passages to form one unit, the pressure fluid entering one cylinder and exhausting through the other, my chief object being to enable such types of engine to be made in a simple 15 manner and of parts easily assembled and taken apart and so arranged as to avoid difficulties due to unequal expansion.

According to my invention I make the two cylinders and connecting passages in the 20 form of two single-walled U-shaped tubes, inverted one over the other and connected together through flanges which are set back from the joining edges to form an annular channel around the middle of each cylinder, 25 within which channels are situated annular inlet and exhaust boxes which may be secured by the connecting bolts of the flanges.

The complete duplex cylinder, with its 30 annular boxes and branches, is mounted upon a base or support preferably by means of the cylinder flanges above referred to. The said base may form part of a tank within which the duplex cylinder and connected parts are entirely inclosed (or one cylinder only may be so inclosed), the tank acting 35 as a steam jacket in the case of a steam engine or a cooling jacket in the case of an internal combustion engine. Owing to the central method of support of the duplex 40 cylinder and to its simple construction with single walls, difficulties due to differential expansion and contraction between inner and outer walls, such as are commonly experienced, are avoided.

50 In order that the said invention may be clearly understood and readily carried into effect I will describe the same more fully with reference to the accompanying drawings in which:—

55 Figure 1 is a vertical section of an internal combustion engine constructed ac-

cording to my invention and inclosed in a separate tank in a manner which permits of free expansion. Fig. 2 is a plan of the same with the upper U-tube removed and the tank in section. Fig. 3 shows in vertical section the main parts of the engine separated, and Fig. 4 is a vertical section of a steam engine embodying my improved construction.

A, A' are the two single walled U-shaped tubes, each comprising cylindrical arms of large diameter and a contracted connecting passage *a* of Venturi form. The lower tube A' has glands *a'* through which the piston rods *b* of the pistons B pass.

C, C' are the annular inlet and exhaust boxes secured between the flanges *a²*, set back a short distance from the meeting edges of the tubes and adapted to receive securing bolts which connect the U-shaped tubes A and A' together and also hold the annular boxes in the channels between the flanges. The boxes are provided with charging and discharging branches *c*, connected to inlet 80 and exhaust pipes.

D is the base on which the cylinders are mounted by means of the supports or standards *d*, carrying the engine through the flanges *a²*.

Referring to the internal combustion engine shown in Figs. 1, 2 and 3 the inlet box C may be made with a horizontal partition *c'* dividing the box into two chambers, through one of which air is allowed to enter the cylinder while the other serves for the admission of the fuel. The meeting edges of the U-tubes are formed with the notches *a³* extending around the circle, these notches forming the inlet and outlet ports in the twin cylinders when the U-tubes are united. The complete cylinders are inclosed in the tank E mounted on the base D and serving to receive the cooling water, which circulates around every part of the cylinders. The tank is provided with apertures *e* in its sides allowing connection to be made between the charging and discharging branches *c* and inlet and exhaust pipes external to the tank. To prevent escape of water thin expansion covering plates *e'* are provided, covering the clearance space between the edges of the tank apertures and the branches *c*. The base D is provided with corresponding apertures *d'* and covering plates *d'* for the glands *a'*. The plates *e'* and *d'* are shown as flat sliding plates, which afford a yield-

ing connection between the tank and base and the other parts to permit of relative expansion between the engine and tank. The supports or standards d are provided with openings d^3 to allow the cooling water to have free access to the lower part of the engine and to permit the lower connecting passage a of the cylinders to take up its proper position, the openings at the inner or adjacent sides of the supports being carried to the top.

The pistons B are connected to cranks set at an angle to each other, so that, as shown in Fig. 1, the exhaust piston, which is at the right hand side, is given a forward lead and uncovers the exhaust ports before the other piston uncovers the inlet ports. By this means the exhaust is rendered more efficient. The exhaust is also closed before the inlet and a fuller charge is thus obtained.

The engine illustrated is a double acting one and the air and fuel are admitted alternately at each side of the left hand piston, passing through the restricted Venturi passages a into the exhaust cylinder. The charge is compressed by the mutual action of the pistons and fired at the proper point of the cycle, the products of combustion escaping through the ports of the right hand cylinder toward the end of the working stroke, and the fresh charge, which immediately follows, completing the expulsion of the waste gases.

The steam engine shown in Fig. 4 is of substantially the same construction, comprising the two single walled U-shaped tubes A and A' with Venturi connecting passages a and flanges a^2 securing the annular inlet and outlet boxes C and C' . The inlet box C is in this case of course not divided. The inlet piston B' is of special form as it has to distribute the steam entering at the central ports alternately to each end of the cylinder. This method of operation forms part of the subject of a separate application Serial No. 705,697, filed June 25, 1912. The piston B' is of reduced diameter between the ends so as to form a channel b' which, near the end of each stroke, connects the inlet ports a^3 to a by-pass a^4 , thus admitting the pressure fluid behind the piston and through the Venturi passage into the second cylinder. The exhaust takes place from the right hand cylinder, the piston of which is given a forward lead. As there is less need to jacket the exhaust cylinder the inlet cylinder only may be inclosed in a tank and such a tank E' is indicated in chain lines surrounding the inlet cylinder and leaving the exhaust cylinder unprotected.

The method of mounting the cylinders by the flanges a^2 may be the same as in the case of the engine first described, and both cylinders may be inclosed as in Figs. 1 and 2.

65 The Venturi passages connecting the cyl-

inders in the two types of fluid pressure engine illustrated allow of substantial separation of the cylinders without much loss of power, as the flow of the fluid through passages of this type meets with very little resistance. The shape of the passages gives reduced clearances and avoids undue fluid friction and in the case of an internal combustion engine enables the scavenging air, which is blown through into the exhaust cylinder in advance of the explosive charge by means of a scavenging pump, to maintain an even front and to prevent the following charge breaking through owing to irregular movements.

It may in some cases be found desirable to suspend the engine from the top instead of mounting it upon a base, the advantages of free expansion being obtained in either case.

It is to be understood that I use the term "fluid pressure engine," except where otherwise defined, to include an internal combustion engine.

What I claim and desire to secure by Letters Patent of the United States is:—

1. A fluid pressure engine with two communicating cylinders side by side, comprising two U-shaped single walled tubes each constituting one half of both cylinders and also a connecting passage, and means for connecting the said U-tubes together at their edges.

2. In a fluid pressure engine with two communicating cylinders side by side, two U-shaped single walled tubes, an annular flange set back from each end of both tubes, means for connecting the said U-tubes together by their flanges to form the two cylinders and connecting passages, and annular inlet and exhaust boxes in the channels formed by the said flanges.

3. In a fluid pressure engine with two communicating cylinders side by side, two U-shaped single walled tubes, an annular flange set back from each end of both tubes, means for connecting the said U tubes together by their flanges to form the two cylinders and connecting passages, and annular inlet and exhaust boxes in the channels formed by the said flanges, the inlet box having a horizontal partition separating the said box into air and fuel admission chambers.

4. A fluid pressure engine with two communicating cylinders side by side, comprising two U-shaped single walled tubes each constituting one half of both cylinders and also a connecting passage, means for connecting the said U tubes together at their edges, and a removable inclosing tank.

5. A fluid pressure engine with two communicating cylinders side by side, comprising two U-shaped single walled tubes each constituting one half of both cylinders and also a connecting passage, means for connecting the said U tubes together at their edges,

a tank, and means for supporting the cylinders removably within the tank at about the middle of the cylinders.

6. A fluid pressure engine with two communicating cylinders side by side, comprising two U-shaped single walled tubes each constituting one half of both cylinders and also a connecting passage, means for connecting the said U tubes together at their edges, a tank, inwardly extending supports projecting to about the middle of the said tank and means for securing the said cylinders to these supports.

7. A fluid pressure engine with two communicating cylinders side by side, comprising two U-shaped single walled tubes each constituting one half of both cylinders and also a connecting passage, means for connecting the said U tubes together at their edges, a tank inclosing the said cylinders and provided with apertures for the piston rods

and connections of the engine, means for supporting the cylinders removably within the tank and yielding covering plates for the tank apertures permitting of free relative expansion and contraction of the engine and tank without allowing escape of fluid from the tank.

8. A fluid pressure engine with two communicating cylinders side by side, comprising two U-shaped single walled tubes each constituting one half of both cylinders and also a contracted connecting passage of Venturi form, and means for connecting the said U tubes together at their meeting edges.

In testimony whereof I affix my signature in presence of two witnesses.

ALAN ERNEST LEOPRIC CHORLTON.
